UNITED STATES PATENT OFFICE.

LOUIS ROTH, OF ROSELLE, NEW JERSEY, ASSIGNOR TO STERLING BRONZE COMPANY,
OF NEW YORK, N. Y., A CORPORATION OF NEW YORK.

DESIGN FOR AN ORNAMENT FOR AUTOMOBILE RADIATOR.

Application filed August 27, 1927. Serial No. 23,232. Term of patent 14 years.

To all whom it may concern:

Be it known that I, LOUIS ROTH, a citizen of the United States, residing at Roselle, county of Union, and State of New Jersey, have invented a new, original, and ornamental Design for an Ornament for Automobile Radiator, of which the following is a specification, reference being had to the accompanying drawing, forming part hereof.

Figure 1 is a front view of an ornament for an automobile radiator showing my design.

Figure 2 is a side view of an ornament for an automobile radiator showing my design.

I claim:

The ornamental design for an ornament for automobile radiator, as shown.

LOUIS ROTH.
